Design No. 3,595, dated August 3, 1869.

DESIGN FOR A TRADE-MARK.

The Schedule referred to in these Letters Patent and making part of the same.

To all whom it may concern:

Be it known that I, JAMES L. BRICKEY, of Hannibal, in the county of Marion, and State of Missouri, have invented a new and valuable Design for Trade-Mark; and I do hereby declare that the following is a full, clear, and exact description of the construction and operation of the same, reference being had to the annexed drawing, making a part of this specification, and to the letters and figures of reference marked thereon.

My trade-mark consists mainly in the figure of a crow, with the head of a cock, as represented on the drawing.

Said animal is represented as standing upon a log, and the words "Jim Crow," "Flounders," "Manufac-

tured by J. L. Brickey & Co., Hannibal, Mo.," and "Open this Head," are arranged around said figure in the manner shown.

What I claim as my invention, and desire to secure by Letters Patent, is—

The design for a trade-mark herein set forth, substantially as shown and described.

In testimony that I claim the above, I have hereunto subscribed my name, in the presence of two witnesses.

JAS. L. BRICKEY.
